CLAIM

The ornamental design for a projectile as shown and described.

DESCRIPTION

FIG. 1 is a perspective view of the first embodiment of a projectile showing our new design, wherein the opposite perspective view is identical thereto;

FIG. 2 is a front view thereof, the shot is rotationally symmetric about a longitudinal axis wherein the view from the rear and sides are identical thereto;

FIG. 3 is a top view thereof, the shot is symmetric about a horizontal axis wherein the view from the bottom is identical thereto;

FIG. 4 is a perspective view of the second embodiment of a projectile showing our new design, wherein the opposite perspective view is identical thereto;

FIG. 5 is a front view thereof, the shot is rotationally symmetric about a longitudinal axis wherein the view from the rear and sides are identical thereto;

FIG. 6 is a top view thereof, the shot is symmetric about a horizontal axis wherein the view from the bottom is identical thereto;

FIG. 7 is a perspective view of the third embodiment of a projectile showing our new design, wherein the opposite perspective view is identical thereto;

FIG. 8 is a front view thereof, the shot is rotationally symmetric about a longitudinal axis wherein the view from the rear and sides are identical thereto; and,

FIG. 9 is a top view thereof, the shot is symmetric about a horizontal axis wherein the view from the bottom is identical thereto.

The dash-dot broken lines in FIGS. 7-9 disclose boundaries of claimed design and indicate indeterminant length; any portion between these dash-dot broken lines embraced by

(Continued)

brackets depict indeterminate length and form no part of the claimed design. The appearance of any portion of the projectile between the dash-dot broken lines from no part of the claimed design.

1 Claim, 9 Drawing Sheets
